UNITED STATES PATENT OFFICE.

DAVID E. HUNTER, OF MUSKEGON, MICHIGAN, ASSIGNOR TO THE SHAW-WALKER COMPANY, OF MUSKEGON, MICHIGAN, A CORPORATION OF MICHIGAN.

SECTIONAL FILING-CABINET.

1,240,851.

Specification of Letters Patent. Patented Sept. 25, 1917.

Application filed August 28, 1916. Serial No. 117,163.

To all whom it may concern:

Be it known that I, DAVID E. HUNTER, a citizen of the United States, and a resident of Muskegon, in the county of Muskegon 5 and State of Michigan, have invented certain new and useful Improvements in Sectional Filing-Cabinets, of which the following is a specification.

My invention relates to sectional filing 10 cabinets, particularly to cabinets in which the sections are entirely constructed of sheet metal.

The object of the invention is to provide 15 means for preventing longitudinal, transverse and vertical displacement of the sections after they are placed one on top of the other. Metal pieces, which may be in the form of sheet metal plates, are secured at the lower corners of each section to extend 20 downwardly sufficiently to receive between them the top of a lower section in such manner as to prevent longitudinal and transverse relative displacement of the sections, interengagement being provided between the 25 plates of one section and a lower section for interlocking against vertical displacement. On the lower section the plates will extend downwardly sufficiently to act as legs for a tier of sections to hold it raised above the 30 floor.

My invention is shown in detail on the accompanying drawing in which—

Figure 1 is a perspective view of two cabinet sections mounted one on the other;

Fig. 2 is an enlarged sectional view on plane 2—2, Fig. 1, showing the interlocking connection between sections;

Fig. 3 is an enlarged sectional view on plane 3—3, Fig. 1, of the rear upper corner 40 of the lower section.

My invention is adapted for application to 45 sections of different construction. In the drawings each section comprises a rectangular drawer or container 5 and a rectangular housing structure 6 into which the drawer is slid in a well known manner. In the housing shown front and rear rectangular frames 7 and 8 are formed of channel iron and at the lower corners are connected by longitudinally extending sheet metal pieces bent 50 at right angles to form the vertical walls 9 and 9' and the horizontal walls or ledges 10 and 10', the ledges 10 and 10' forming the supports for the bottom 11 of the drawer 5. At the top the frames 7 and 8 are connected

by a sheet metal piece which is bent to form the top 12 and the sides 13 and 13'; these upper side sections being in the planes of the lower side sections 9 and 9' respectively, but separate therefrom in order to lighten the 60 structure. The walls described are secured at their ends to the inner sides of the frames 7 and 8.

When the sections are placed one on the other the front frames 7 will rest on each other and likewise the rear frames 8 will rest on each other in vertical alinement. To prevent longitudinal and transverse displacement of the sections metal pieces 14, 15, 16 and 17 are secured at the respective lower 70 corners of each section, and project downwardly a sufficient distance below each section to engage with the lower section at the corners thereof to prevent transverse relative displacement of the sections. I have 75 shown the pieces in the form of rectangular sheet metal plates secured to the sides 9 and 9' respectively, preferably by means of spot welding. As shown these plates are secured alongside of the frames 7 and 8 so that when 80 one section is placed on another, the projecting ends of the plates of the upper section will engage against the upper side wall sections 13 and 13' of the lower section to prevent relative transverse displacement, 85 and will also engage against the frames 7 and 8 to lock the sections against relative longitudinal displacement. The plates being smooth sections can be readily brought together or can be readily separated, but when 90 once brought together they are rigidly locked against relative transverse or longitudinal displacement. On the lowest section the downwardly projecting plates will act as legs to support the tier above the floor suffi- 95 cient to permit cleaning of the floor.

In order to lock the sections at the rear against vertical displacement as well as longitudinal and transverse displacement, the rear plates 14 and 16 have rearward projections or tongues 18 at their rear lower corners for engaging in slots or sockets 19 formed in the front wall of the rear frames 8. When sections are arranged in vertical alinement the tongues will engage in the 105 sockets and will lock the sections together vertically. The sections can be readily separated by raising up the front end of the top section sufficient to raise the front plates 15 and 17 above the next lower section and 110

- to withdraw the tongues 18 out of the slots 19, whereupon the top section can be pulled forwardly along the lower section and then lifted therefrom. To apply one section to 5 the other, its front end is raised and its rear frame 8 brought against the rear frame of the lower section, and the top section then brought down to horizontal position to bring the tongues into the slots and the plates 10 against the sides of the lower section and against the front and rear frames of the lower section, and the sections will then be in accurate vertical alinement and will be so maintained. The plates being of thin 15 sheet metal are well within the outer edges of the frames 7 and 8 and when several tiers of sections are placed alongside of each other, the respective frames 7 and 8 can be brought into close contact.
- 20 I thus produce a very simple and efficient arrangement for interlocking the sections of a filing cabinet, the plates being readily stamped from sheet metal and rigidly secured preferably by welding. The plates 25 of the bottom section form neat and strong supporting feet for holding the tier above the floor.

I do not, of course, desire to be limited to the exact construction and arrangement

shown as modifications are no doubt possible which would still come within the scope of the invention. I claim the following:

In an all metal sectional filing cabinet, the combination of front and rear rectangular supporting frames, top, side and bottom 35 walls extending between and secured to said frames, plates welded to said side walls at the lower corners thereof and alongside of said front and rear frames, said plates extending downwardly sufficiently to engage 40 against the side walls of a lower section of a tier and to abut against the front and rear walls of such lower section whereby to prevent longitudinal and transverse relative displacement of the sections, said plates also 45 acting as legs for separate sections or for the lowermost section of a tier, the rear frames of each section having notches and the rear plates having tongues for extending into said notches when the sections are 50 placed one on top of the other whereby to prevent relative vertical displacement of such sections.

In witness whereof I hereunto subscribe my name this 16th day of August, A. D., 55 1916.

DAVID E. HUNTER.
